UNITED STATES PATENT OFFICE

FRANK SMITH BLUE, OF CARTHAGE, NORTH CAROLINA

COMBINED BULLETIN AND BLACKBOARD

Application filed August 9, 1930. Serial No. 474,214.

This invention relates to the bulletin and black board which constitutes the subject matter of my U. S. Letters Patent No. 1,727,332, granted September 10, 1929, and which comprises a support in the form of a stand adapted to be mounted upon a desk, counter, floor or the like, and a plurality of panels adapted to be written upon by chalk or the like and swingingly connected together and to the support to permit each side of each panel to be squarely presented to the observers.

The present invention has for one of its objects to mount the panels on a hanger or bracket which shall be adapted to be secured to a wall or wall black board or to a wall between two black boards, to the end that the bulletin and black board may be used to the best advantage in a class room or the like.

The present invention has for a further object to swingingly connect the panels to the hanger or bracket in a manner to permit them to be moved easily and without noise.

The present invention has for a still further object to provide means through the medium of which the panel being written upon may be held against swinging movement.

With the foregoing and other objects in view, the nature of which will appear as the description proceeds, the invention consists in the construction, combination and arrangement of parts hereinafter fully described and claimed, and illustrated in the accompanying drawings, wherein:—

Figure 1 is a sectional view taken on a plane extending horizontally and centrally through the bulletin and black board;

Figure 2 is a sectional view taken on a plane extending vertically and centrally through the bulletin and black board;

Figure 3 is a view in front elevation of the hanger or bracket of the bulletin and black board;

Figure 4 is a view similar to Figure 1 illustrating the means by which one of the panels of the bulletin and black board may be supported against rearward movement, and

Figure 5 is a sectional view taken on the plane indicated by the line 5—5 of Figure 4.

Referring in detail to the drawings, 1 des-

ignates the panels and 2 the hanger or bracket of the bulletin and black board. The panels 1 may be of rectangular or any other desired formation in elevation, and may be made of any material having a surface adapted to be written upon by chalk or the like. The panels 1 are mounted in frames 3 which are of the open formation to expose both surfaces of each panel and thus permit both surfaces to be written upon. The hanger or bracket 2 is of all metal construction and comprises a vertical bar 5 and horizontal arms 6. The arms 6 are provided with attaching members 7 which are formed integrally therewith and arranged at right angles thereto and which are secured to the bar 5 by rivets 8.

The attaching member 7 of the upper arm 6 extends upwardly therefrom and the attaching element of the lower arm 6 extends downwardly therefrom. The bar 5, arm 6 and attaching members 7 are similar as to width, and the attaching members lie in full abutting contact with the bar. The bar 5 is provided between the arms 6 with openings 9, and the attaching members 7 and the bar are provided with openings 10, for the reception of elements 11 for securing the hanger or bracket to a wall 12.

The bulletin and black board may comprise one or more units of the panels 1, each unit consisting of two panels. The panels of each unit are connected together by hinges 13, and one of the panels of one unit is connected to a panel of the other unit by hinges 14. The panels are arranged between the arms 6 and are swingingly connected thereto by the pintles 15 of the hinges 14. The pintles 15 pass through openings 16 in the arms 6, and the opening of the upper arm located nearer the bar 5 than the opening of the lower arm so as to support the panels 1 in an upwardly and forwardly inclined position. The panels 1 are connected together and to the hanger 1 for individual swinging movement about upwardly and forwardly inclined axes. They may be arranged with one extending to the right and the others extending to the left from the hanger or bracket or they may be arranged with one extending to the left and

the others extending to the right from the hanger or bracket.

In order to permit the panels 1 to be moved easily and without noise, they are supported upon the arms 6 by anti-friction bearings 17, each consisting of upper and lower discs or retainers 18 and 18^a, respectively, and balls 19 between the retainers. The retainers 18^a rest upon the upper surfaces of the arms 6, and these and the retainers 18 are provided with openings 20 for the reception of the hinge pintles 15. The lower hinge 14 has a barrel extension 21 which rests upon the lower bearing disc 18, and a nut 22 secured to the upper end of the pintle 15 of the upper hinge 14 rests upon the upper bearing disc 18. As they are supported by the bearings 17, the panels 1 may be moved with comparatively little or no effort.

When the panels 1 are so arranged that only one of them projects to the right from the hanger or bracket 2, means are provided for holding such panel against forward movement so that it may be easily written upon, and such means are associated with one panel of each unit. These means comprise latch bolts 23 connected to two of the panel frames 3, as at 24, for swinging movement about horizontal axes. The latch bolts 23 are each provided at its free end with a downturned hook 25 adapted to be engaged with a keeper 26 fixed to the wall 12 to the right of the hanger or bracket 2. When the latch bolt 23 is in engagement with the keeper 26, it holds the panel 1 with which it is associated against movement in the direction of the wall 12, and in view thereof, such panel is held against movement and may thus be easily written upon.

The keeper 26 is provided at its upper end with a hook 27 with which the latch hook 25 engages, and these hooks are curved on the arc of a circle having the pintle 6 for its center, so that the latch hook will move automatically out of engagement with the keeper hook when the pintle is swung to the left. The keeper 26 functions merely to support the latch bolt 23 engaged therewith so that the latch bolt may in turn hold the panel with which it is associated against forward movement. When neither is engaged with the keeper 26, the latch bolts 23 extend downwardly from their pivots 24.

If desired, one panel frame 3 of each unit may be provided with a beveled vertical edge 28, as shown in Figure 1, in order to permit that panel extending to the right from the hanger or bracket 2 to be swung against the wall 12 so that it will be held against movement when being written upon. When a panel frame of each of the units is provided with a beveled edge, the latch bolts 23 and the keeper 26 will not be employed.

From the foregoing description, taken in connection with the accompanying draw-

ings, it should be apparent that the hanger or bracket 2 permits the panels 1 to be firmly secured to a wall at such height that all within in the class room or the like may clearly see the matter written upon the panels. The panels 1 may be moved consecutively to present their surfaces to the observers.

The hanger or bracket 2 permits the panels 1 to be secured to a wall black board or to a wall between two black boards, and each provides a private black board for the teacher's use. As the panels 1 are connected to the hanger or bracket 2 for swinging movement about inclined axes, those panels that are arranged one in advance of the other will not move accidentally from such position. The panels are valuable for lectures, outline work and the like.

While I have described the principle of the invention together with the structure which I now consider the preferred embodiment thereof it is to be understood that the structure shown is merely illustrative and that such changes may be made, when desired, as fall within the scope of the invention as claimed.

I claim:

A device of the character set forth comprising a bracket adapted to be secured to a wall, panels pivoted to the bracket, a keeper provided with a curved hook and adapted to be secured to the wall at one side of the bracket with its hook arranged in the arc of a circle having the pivot of the panels for its center, and a latch bolt connected at one of its ends to one of the panels for swinging movement about a pivot right angularly related to the pivot of the panel, the latch bolt being adapted to rest at its free end upon the keeper hook and provided at said end thereof with a downturn hook adapted to engage the keeper hook and be moved out of engagement therewith when the panel carrying the latch bolt is swung in one direction.

In testimony whereof I hereunto affix my signature.

FRANK SMITH BLUE.
